CLOTH FINISHING MACHINE

John F. Bannon, Lonsdale, R. I.

Application November 10, 1934, Serial No. 752,418

3 Claims. (Cl. 26—42)

My invention relates to a cloth finishing machine such as is used for shrinking shirtings and similar fabrics.

In cloth shrinking machines of the above type 5 a large rotatable drum heated by steam or other suitable means is provided and the moistened or damp fabric to be treated or shrunk is brought into contact with the peripheral surface of the drum and moves with the latter throughout a 10 large portion of its periphery and is then withdrawn. On coming into contact with the rotating heated drum, the fabric to be treated is brought into contact with an endless blanket and passes with the blanket over a roll and thence 15 throughout its movement and contact with the drum is held tightly against the surface of the drum. The blanket then continues out of contact with the drum and preferably through a drying mechanism, back to its original position 20 into contact with a succeeding length of the fabric.

In passing over the entrance roll the fabric is 25 on the outer curved surface of the blanket and, consequently, has a greater length for a given arc or curvature and then in coming into contact with the drum, this relation is reversed so that the length of fabric originally in contact with a given length of the blanket is now of slightly less 30 length than its corresponding blanket portion. This provides for the change in length of the fabric during the shrinking operation. As the shrinkage is different for different fabrics, this difference may be accommodated by selecting a 35 proper thickness of the blanket for the particular shrinkage of the fabric to be treated.

Heretofore this has been done by employing 40 blankets of different thicknesses, one for each gradation in shrinkage of the fabric. This has not only necessitated the maintenance of a large 45 number of blankets of assorted thicknesses, but with each change of fabric to one of different shrinking qualities the entire blanket must be removed from the machine and a new one substituted. As this generally involves dismounting 50 the rollers and other apparatus through which the blanket must pass, it involves a very considerable expense.

My present invention avoids the above difficulties and provides a means whereby the various 55 blanket thicknesses required at the entrance roll may be attained with a blanket having an unvarying thickness and whereby the effective thickness of the blanket assembly at the entrance roll may be quickly and easily adjusted without

removing the entire endless blanket from the machine.

The various features of the invention are illustrated in the accompanying drawing, in which—

Fig. 1 shows diagrammatically a side elevation 5 of a fabric finishing machine embodying a preferred form of the invention, driving mechanism for the machine being omitted to more clearly set forth the invention.

Fig. 2 is a front view of a portion of the entrance roll mechanism, and

Fig. 3 is a side elevation of a part of the mechanism showing the entrance roller construction.

In my invention an endless blanket is mounted in the same general manner as is customary with machines of this type but an auxiliary means is employed to provide an effective blanket thickness at the entrance roller that may be readily adjusted to suit the requirements of different fabrics. In the preferred form of the invention 15 this auxiliary means comprises an inner endless blanket having a much smaller length than that of the main blanket and lying between the main blanket and the entrance roller so that it adds its thickness effectively to that of the main blanket. The auxiliary blanket may be kept taut on the roll by means of a second roll which may be 20 adjusted to tighten the auxiliary blanket on the entrance roll and also to tighten or loosen it against the heated rotating drum. To adjust 25 the effective thickness at the entrance roll it is, therefore, only necessary to loosen and remove the auxiliary blanket and replace it with one of 30 appropriate selected thickness.

Referring to the accompanying drawing, a 35 fabric 10 to be shrunk or finished is drawn below and about a guide roller 11, thence upwardly and about an entrance roller 12 and into contact with a heated drum 13 rotatably mounted on a supporting frame 14. As the fabric 10 passes 40 upwardly and about the entrance roller 12, it rests on the surface of an endless blanket 15 and passes with this blanket into contact with the drum 13, the fabric being between the blanket 15 and the drum 13. It will be apparent that the 45 radius of the fabric 10 as it passes about the roller 12 is greater than that of the roller and of the blanket 15 and, consequently, has a greater length for a given angle. As the fabric passes 50 into contact with the drum 13 this relation is reversed so that the fabric may shrink without changing its surface contact with the blanket. The blanket and fabric then rotate with the heated drum throughout the greater part of the 55 periphery of the latter, the cloth being dried

by this passage and then leaving the drum below an exit roller 16. The blanket 15 then returns about a succession of rollers 17 and a drying cylinder or drum 18 to its original position 5 over the entrance roller 12.

In my invention an auxiliary inner blanket 19 is provided between the entrance roller 12 and the blanket 10. The auxiliary blanket 19 is held tautly on the roller 12 by means of an adjustable roll 20. The relation of the blanket 19 to the 10 blanket 15 is such that a contraction of the latter takes place as it passes from the roller 12 to the drum 13 so that the effect is as though a blanket were used of substantially the thickness 15 of the blanket 15 plus the thickness of the blanket 19. The blanket 19 passes for a short distance in contact with the blanket 15 and then returns about the roller 20. In the further progress of the blanket 15 and fabric 10 about the drum 13 20 to the exit roller 16 the effective thickness of the blanket is of no great consequence, so that by the use of the above auxiliary blanket the effect of blankets of different thicknesses may be obtained by merely changing the blanket 19. This is a relatively much simpler matter than 25 changing the blanket 15, as it involves merely a loosening of the roller 20 and then slipping out the auxiliary blanket without disturbing the main blanket except at the entrance roller 12 whereas, to remove and replace the main blanket requires 30 its removal from each of the rollers 17 and the drying mechanism 18.

To remove the auxiliary blanket 19, the roller 20 is so mounted that it may be lifted upwardly 35 and away from the drum 13. For this purpose the bearing 21 of the roller 20 is supported, as shown in Figs. 2 and 3, by a pair of screwthreaded rods 22 and 23 at right angles to each other and passing through brackets 24 and 25. By loosening securing nuts and lifting the rod 22 upwardly, the roller 20 is lifted and, by moving the rod 23 outwardly, it is shifted away from the drum 13. This loosens the auxiliary blanket 19 so that it may be readily slipped from its rolls. The main 40 blanket 15 may also be loosened by raising the outlet roller 16 which is for this purpose mounted in adjustable bearings 26 as indicated at Fig. 1.

Both of the blankets 15 and 19 being loosened, the entrance roller 16 may be slid outwardly of the bifurcated or slotted bracket 27 in which it is supported, thus rendering it easier to remove and replace the auxiliary blanket 19. 5

Through the above invention, therefore, it is possible to obtain effective blanket thicknesses at the entrance roll while employing but a single blanket for several different types of fabric to be treated or to several different conditions of 10 shrinkage. Also the changing in this effective blanket thickness requires a minimum of adjustment and enables the main blanket to remain in position thereby greatly facilitating the 15 changes required for different shrinkages.

What I claim is—

1. A cloth finishing machine comprising a rotatable drum, an endless blanket moving in contact with the surface of said drum throughout a portion of the periphery of the latter, an entrance roller for bringing successive lengths of said blanket into contact with the rotating surface of the drum, and an auxiliary blanket between said entrance roller and said main blanket. 20

2. A cloth finishing machine comprising a rotatable drum, an endless blanket moving in contact with the surface of said drum throughout a portion of the periphery of the latter, an entrance roller for bringing successive lengths of said blanket into contact with the rotating surface of the drum, an auxiliary blanket between said entrance roller and said main blanket, and a second roller adjustable to hold said auxiliary blanket taut about said entrance roller. 25

3. A cloth finishing machine comprising a rotatable drum, an endless blanket moving in contact with the surfaces of said drum throughout a portion of the periphery of the latter, an entrance roller for bringing successive lengths of said blanket into contact with the rotating surface of the drum, an auxiliary blanket between said entrance roller and said main blanket, a second roller about which said auxiliary blanket passes, and an adjustable mounting for said second roller comprising supports adjustable vertically and laterally. 35 40 45
